UNITED STATES PATENT OFFICE.

JOHN T. WAUGH, OF EAST SAN DIEGO, CALIFORNIA.

TURBINE.

1,391,434.

Specification of Letters Patent. Patented Sept. 20, 1921.

Application filed June 15, 1920. Serial No. 389,200.

To all whom it may concern:

Be it known that I, JOHN T. WAUGH, a citizen of the United States, residing at East San Diego, in the county of San Diego and State of California, have invented certain new and useful Improvements in Turbines, of which the following is a specification.

My invention relates to turbines more particularly fluid pressure and expansion actuated turbines actuated by steam, compressed air, gas or like fluids and the objects of my invention are: first, to provide a turbine in which the fluid is conducted 10 from a pressure tank boiler or the like through a housing to graduated sized pockets in proper sequence to provide a maximum of efficiency from the pressure and expansion of the fluid upon a revoluble member; second, to provide a turbine of 15 this class with a plurality of channels of graduated sizes, each provided with a plurality of pockets of relative sizes and with fluid ports whereby the fluid is conducted 20 first to the smallest channel then to a larger and so on; third, to provide a turbine of this class wherein the revoluble member is actuated by fluid pressure and expansion combined; fourth, to provide a turbine of 25 this class in which a maximum of efficiency is utilized from the fluid under pressure; fifth, to provide a turbine of this class in which the power may be increased or multiplied by increasing the number of pocket 30 channels and relative fluid conductors or by multiplying the fluid conductor housings on the same revoluble member; sixth, to provide a turbine of this class which is very 35 simple and economical of construction, efficient in its action, durable, easy to operate, applicable for use universally, compact in 40 form and which will not readily deteriorate or get out of order.

With these and other objects in view as 45 will appear hereinafter my invention consists of certain novel features of construction, combination and arrangement of parts and portions as will be hereinafter described in detail and particularly set forth 50 in the appended claims reference being had to the accompanying drawings and to the characters of reference thereon which form a part of this application in which:

Figure 1 is a side elevational view of 55 my turbine in its simplest form showing the fluid intake and exhaust fragmentarily;

Fig. 2 is a transverse sectional view through 2-2 of Fig. 1; Fig. 3 is an inner view of the housing from the line 3-3 of Fig. 1; Fig. 4 is a detailed fragmentary top view of the revoluble member without the housing; Fig. 5 is a side elevational view of my turbine in slightly modified form from that of Fig. 1; Fig. 6 is a fragmentary top view of the revoluble member only in this modified form; Fig. 7 is another side elevational view in another modified form showing additional channels and multiple housing; Fig. 8 is a sectional view through 8-8 of Fig. 7 and Fig. 9 is a sectional view 70 showing the grooves and housing in multiple form on the one revoluble member.

Similar characters of reference refer to similar parts and portions throughout the several views of the drawings.

The base 1, supporting rods 2, shaft 3, revoluble member 4, intake conductor 5, exhaust conductor 6, and housing member 7 constitute the principal parts and portions 80 of my turbine.

The base member 1 is of suitable size to support the turbine and is provided with two upwardly extending journal supports 1^a in which the shaft 3 is journaled. Secured on the shaft 3 between the members 1^a is the 85 revoluble member 4 which is provided with outwardly extended side flanges 4^a and with a plurality of grooves, in this case I have shown three, 4^b, 4^c and 4^d, although it is obvious that a more or less number may be 90 used if desired. On opposite sides of these grooves are upwardly projecting portions 4^e, 4^f, 4^g and 4^h which form well defined walls between the channels 4^b, 4^c and 4^d. In the grooves 4^b are positioned a plurality of small 95 pockets 4ⁱ of relatively small size. In the groove 4^c are a plurality of larger pockets 4^j and in the groove 4^d are a plurality of still larger pockets 4^k, all of which are deeper 100 at their larger end and shallower at their smaller end forming an abutment for the fluid. Mounted over this revoluble member 4 and provided with grooves conforming to the extended portions 4^e, 4^f, 4^g and 4^h is a 105 housing 7 which is preferably made in two parts separated in the middle longitudinally so that it may be readily placed in position over the revoluble member and secured together by means of bolts 7^a and provided with a gasket 7^b between the two members 110 to provide a tight joint as shown best in Fig. 2. This housing 7 is provided with inwardly

extended flanges 7^c which are adapted to rest on the flanges 4^a which form bearings and the members 4^d , 4^f , 4^g and 4^h rest in conforming grooves in said housing thus providing a plurality of varying sized well defined grooves. This housing 7 is provided with a fluid inlet port 7^d which communicates with the pockets 4^i in the groove 4^g , then with another port 7^e which connects these pockets 4^i at a spaced position with the pockets 4^j , then with another port 7^f connecting the pockets 7^j with the pockets 7^k in the proper sequence, then another port connecting the pocket 7^k with the exhaust pipe 6 so that this housing is provided with ports spaced in proper sequence connecting first with the pockets 4^i , then from the pockets 4^i through the wall of the housing to the pockets 4^j , then from the pockets 4^j in proper sequence through the housing to the pocket 4^k , then from the pocket 4^k through the housing to the exhaust 6 . This housing is supported and secured in position by means of the supporting rods 2 which extend through lugs 7^h on the housing 7 and are locked on each side by nuts on said rods. The other ends of said rods are secured in lugs 1^b on the base 1 and locked by means of nuts on the rods 2 .

30 In the modified construction shown in Figs. 5 and 6 of the drawings the large sized pockets in one of the channels face in the reverse direction and the fluid is ported first to the smaller pocket, then to the next larger pocket, then to the exhaust while there are another set of ports in said housing which port the fluid from the intake in the opposite direction through the housing and communicate with the larger pocket which provides for the reverse revolution of the revoluble member, it being noted, however, that the number of series of pockets may be increased as desired for increasing the power. In the further modified construction shown in Figs. 7 and 8 of the drawings there are two housings 7 and 8 connected together by tie rods 8^a on lugs on said housings. The housing 7 is ported similar to the housing 7 as described in Fig. 1 of the drawings and communicates with the three series of pockets 4^i , 4^j and 4^k but in this structure there are two additional series of pockets 4^l and 4^m and the housing 8 is provided with ports which connect with the connecting conductor 8^b which connects the exhaust of the housing 7 with the intake of the housing 8 and ports the fluid first to the pocket 4^l , then through the housing to the pocket 4^m , then through the housing to the exhaust 5 in their proper sequence and spaced relation. In the modified form of construction shown in Fig. 9 of the drawing there are two units of three series of pockets each shown in the revoluble member thus showing the application of the device having a plurality of these units placed

side by side on the revoluble member and a plurality of housings conforming thereto positioned thereon. The pockets and ports in one of these may run in one direction and the other in the opposite direction providing for direct and reverse action if desired.

Though I have shown and described a particular construction, combination and arrangement of parts and portions and certain modifications thereof I do not wish to be limited to this particular construction, combination and arrangement, nor to the modifications thereof but desire to include in the purview of my invention the construction, combination and arrangement substantially as set forth in the appended claims.

It is obvious that with this construction there is provided a fluid turbine which may be operated by steam, compressed air, gas, or any expansive fluid in which the fluid is conducted under pressure to a plurality of series of gradually increasing sized pockets which form abutments for revolving a revoluble member by reason of the pressure of the fluid passing into said pocket and utilizing the same pressure in another larger sized pocket in series together with any expansion that takes place during its passage; that the full pressure and expansive quantity of the fluid may be utilized thus providing great efficiency and that the same may be used in either direction for direct or reverse movement or multiplied as desired in the one turbine unit.

Having thus described my invention what I claim as new and desire to secure by Letters Patent is:

1. A turbine including, a revoluble member provided with a face in the middle of its periphery concentric with the axis of said revoluble member and with oppositely disposed faces at an angle thereto and provided with extended seal portions at opposite sides of each of said faces forming three independent grooves, each groove provided with a series of pockets therein and a housing provided with faces adapted to fill the grooves in said revoluble member and with notches to receive the seal portions and a plurality of ports connecting with a fluid pressure tank and communicating with the separate series of pockets in said revoluble member consecutively.

2. A turbine including, a revoluble member provided with a face in the middle of its periphery concentric with the axis of said revoluble member and with oppositely disposed faces at an angle thereto and provided with extended seal portions at opposite sides of each of said faces forming three independent grooves, each groove provided with a series of pockets therein and a housing provided with faces adapted to fill the grooves in said revoluble member and with notches to receive the seal portions and a

plurality of ports connecting with a fluid pressure tank and communicating with the separate series of pockets in said revoluble member consecutively and means for supporting said housing in certain position relatively to said revoluble member.

3. A turbine including, a revoluble member provided with a face in the middle of its periphery concentric with the axis of said revoluble member and with a plurality of faces positioned on opposite sides of said first-mentioned face and receding therefrom on an angle, each of said faces being provided with an extended seal portion on opposite sides and each face provided with a series of pockets, the series of pockets in one face being of different size from the other, increasing from the middle and a housing provided with faces adapted to fit against the face on said revoluble member between the seal portions and provided with ports for conducting fluid to the pockets in the middle face of said revoluble member and with other ports in said housing from the pockets in said middle face to larger pockets on the angular faces.

4. A turbine including, a revoluble member provided with a face in the middle of its periphery concentric with the axis of said revoluble member and with a plurality of faces positioned on opposite sides of said first-mentioned face and receding therefrom on an angle, each of said faces being provided with an extended seal portion on opposite sides and each face provided with a series of pockets the series of pockets in one face being of different size from the other increasing from the middle and a housing provided with faces adapted to fit

against the face on said revoluble member 40 between the seal portions and provided with ports for conducting fluid to the pockets in the middle face of said revoluble member and with other ports in said housing from the pockets in said middle face to larger 45 pockets on the angular faces, a base member on which said revoluble member is supported and adjustable means connecting said base member with said housing.

5. A turbine including, a revoluble member 50 provided with a flat middle portion on its periphery concentric with the axis of rotation, angular portions on opposite sides thereof receding toward said axis and provided with seals between said flat portion 55 and said angular portion and provided with a plurality of pockets of varying size, increasing from the middle portion outwardly, a housing provided with conforming surfaces adapted to fit the portions of said revoluble member and with grooves to receive the seal portions, whereby the housing member and revoluble member fit snugly together and said housing provided with ports extending from a fluid pressure tank and 60 communicating with the pockets in said middle portion and other ports in said housing connecting the pockets in said middle portion with the pockets in the outer angular portions whereby the fluid under pressure will pass to the pockets in said middle portion and under expansion will pass through ports in the housing to the pockets in said angular portions.

In testimony whereof I have hereunto set 75 my hand at San Diego, California, this 9th day of June, 1920.

JOHN T. WAUGH.
